UNITED STATES PATENT OFFICE

WALTER E. AESCHBACH AND CARL WICK, OF ST. LOUIS, MISSOURI

DECAPPING TOOL

Application filed February 27, 1930. Serial No. 431,710.

Our invention relates to an improved decapping tool, and has as its objective to provide a tool for the removal of both screw-caps and friction-caps from bottles, jars and other containers.

It consists of a frame having an aperture of converging straight edges, along one of which edges we dispose a fixed gripping strip or element having a biting, preferably saw-toothed, edge, having raking teeth; the other edge of said aperture carrying a sliding element, having humps arranged to center a screw-cap between them, the sliding element being arranged to carry the screw-cap into biting engagement with the gripping element, said biting engagement serving to hold the cap against rotation, whereupon the container is twisted to unscrew it from the cap.

For use in removing a friction cap, we form a hook on one of the outer edges of said frame, which enables the tool to be used as a hand-lever for the removal of such caps.

Drawings

25 In the drawings—

Fig. 1 is a plan view of a tool embodying our invention, mounted in a wall-bracket.

Fig. 2 is a front elevation of the same.

Fig. 3 is a plan view of said tool, being used as a hand-lever in removing a friction-cap.

Description

The frame A is apertured to produce the converging opposed inner straight edges 2 and 3 and the hook 4 is formed on one of the outer edges of said frame A. Upon the face of the frame A the gripping element 5 is fixedly mounted; I have shown it as being mounted removably by means of screws 6. The inner edge of the gripping element 5 is preferably provided with saw-teeth 7, said teeth 7 being raked inwardly when the tool is mounted on the wall-bracket 8 by means of the cleats 9—9. Opposed to the gripping element 5 is the slideable centering element 10 mounted by means of the screws 11 in the slot 12 formed through the frame A.

In the form illustrated the centering element 10 has its inner biting edge formed as

shown, with twin humps 13—13, the projecting edge of each of said humps 13—13 consisting of saw-teeth 14, which teeth 14 are raked in the opposite direction to that of the raking of the teeth 7 on the gripping element 5. The cleats 9 extend in opposite directions from the upper and lower faces of the frame A, so that the frame A may be reversed in the wall-bracket 8 to perform the opposite functions of screwing and unscrewing the screw cap B. In Fig. 1 we have illustrated said screw-cap B in proper engagement with the tool for the purpose of unscrewing and removing said cap B. When it is desired to use the tool for the purpose of seating the cap B, the frame A is reversed in the wall-bracket 8, the screw-cap B is again seated within the tool and rotated in the direction indicated by the arrow in Fig. 2 to screw the cap securely in place.

When it is desired to remove a friction-cap from a container, the tool is removed from its seat in the wall-bracket 8 and used as a hand-tool, the hump 4 engaging the friction-cap C, to pry said cap C from its seat, the application being as shown in Fig. 3.

As is well known in the practical use of screw-caps, such screw-caps are frequently seated so firmly upon the containers when delivered to the consumer, as to make the removal of the screw-cap a matter of great difficulty. By means of our invention it is made possible to secure a bite upon the screw-cap which will enable it to be readily unscrewed from its container.

Various modifications of the illustrated form of our invention may be effected without departure from our actual invention as defined in the appended claims.

We claim—

1. A decapping tool comprising a frame, attaching means on the frame for reversible engagement with a fixed support, said frame being apertured to provide converging opposed inner straight edges, a fixed toothed gripping element on one straight edge, and a slideable gripping element on the other straight edge, said slideable element having a pair of toothed humps.

2. A decapping tool comprising a frame,

attaching means on the frame for reversible engagement with a fixed support, said frame being apertured to provide converging opposed inner straight edges, toothed gripping elements carried by the straight edges, the teeth of one element raked in a direction opposite from the teeth of the other gripping element, one gripping element being slidable to grip an object between the two gripping elements, and the frame being reversible to engage an object therein against movement either in a clockwise or anti-clockwise direction.

In testimony whereof we have hereunto affixed our signatures,

WALTER E. AESCHBACH.
CARL WICK.
